UNITED STATES PATENT OFFICE

155,172

DESIGN FOR A SLIDE PROJECTOR OR SIMILAR ARTICLE

George K. Lewis, Chicago, Ill., assignor to Three
Dimension Company, Chicago, Ill., a corpora-
tion of Illinois

Application January 28, 1949, Serial No. 537

Term of patent 7 years

(Cl. D61—1)

To all whom it may concern:

Be it known that I, George K. Lewis, a citizen of the United States and a resident of the city of Chicago, in the county of Cook and State of Illinois, have invented a new, original, and ornamental Design for a Slide Projector or Similar Article, of which the following is a specification, reference being had to the accompanying drawings, forming a part thereof.

Figure 1 is a top plan view of a slide projector or similar article, showing my new design;

Figure 2 is a side elevational view;

Figure 3 is a side elevational view of the opposite side of Figure 2;

Figure 4 is a front end elevational view thereof; and

Figure 5 is a rear end elevational view of the same.

I claim:

The ornamental design for a slide projector or similar article, substantially as shown.

GEORGE K. LEWIS.
